UNITED STATES PATENT OFFICE

ALBERT BROADMEYER, OF HARRISBURG, PENNSYLVANIA, ASSIGNOR TO THE W. O. HICKOK MFG. CO., OF HARRISBURG, PENNSYLVANIA, A CORPORATION OF PENNSYLVANIA

COUNTING AND TABBING APPARATUS

Application filed November 10, 1926. Serial No. 147,598.

The present invention relates to apparatus for determining a predetermined number of sheets and marking such number.

The object is to provide an apparatus 5 that is entirely practical, and is provided with a marking or indicating mechanism of a novel character.

Two embodiments of the invention are disclosed in the accompanying drawings, 10 wherein:—

Figure 1 is a side elevation of one embodiment,

Figure 2 is a view in elevation of the opposite side to that shown in Figure 1,

15 Figure 3 is a top plan view,

Figure 4 is a detail sectional view on the line 4—4 of Figure 3,

20 Figure 5 is a view partly in elevation and partly in section of the mechanism for severing a strip to produce the tab,

Figure 6 is a horizontal sectional view on the line 6—6 of Figure 5,

25 Figure 7 is a sectional view on the line 7—7 of Figure 6,

Figure 8 is a perspective view of the cam track of the pawl actuating arm,

30 Figure 9 is a detail sectional view on the line 9—9 of Figure 1,

Figure 10 is a detail elevation of the de-35 tent-escapement for the cutter-operating means,

Figure 11 is a detail perspective view of the tab support,

35 Figure 12 is an end elevation of the same,

Figure 13 is a side elevation of a modified form of construction,

40 Figure 14 is a top plan view of the same,

Figure 15 is a view in elevation of the escapement detent employed in this embodiment,

45 Figure 16 is a detail sectional view on the line 16—16 of Figure 14.

In the embodiment disclosed, a suitable frame is employed, comprising side plates 45 17 connected by arch bars 18. This frame is adapted to be mounted on the frame of any well-known type of apparatus for operating on sheets, for example, a ruling machine, and is so disposed that the sheets will pass 50 longitudinally of the side bars. Thus in

Figure 1, there is indicated a portion of a conveyor 19, on which sheets are successively transported.

At one end of the frame, upright standards 20 support a spindle 21, on which is mounted 55 a drum 22 that carries a strip of paper, indicated at 23. This strip of paper is carried about an idler roller 24, and between a lower grooved roller 25 and an upper roller 26, having a peripheral tongue 27 that operates in the groove of the roller 25. After passing between these rollers, the strip slides on a runway 28 supported on one side of the frame, and thence to a cutter designated generally by the reference numeral 29. 60 This cutter may be considered a number-determining member, as hereinafter more fully explained.

A drive shaft 30 is journaled transversely on the frame, and is provided with a pulley 31, by which it may be driven from any suitable source of power. Loosely journaled on said drive shaft 30 is the hub 32 of cam 33. The cam has a friction clutch connection with the shaft 30. This connection, as shown more particularly in Figure 4, preferably consists of a threaded sleeve 34 fixed to the shaft 30 by a set screw 35, having a pair of tension nuts 36 screwed thereon. A collar 37 slidable on the sleeve is located adjacent to the cam 33, and a friction disk 38 is interposed between the collar and the cam. A coiled spring 39 is located on the sleeve, and is interposed between the collar 37 and the nuts 36, thus serving to yieldingly urge 85 the friction disk against the side face of the cam. The tension of this spring is of course varied by adjusting the nuts 36. The cam, as shown in Figure 5, operates against a roller 40 carried by a crank arm 41 that is mounted on a rock shaft 42 carrying another crank arm 43, the parts 41, 42 and 43 constituting in effect a bell crank. Referring now to the cutter 29, as shown in detail in Figures 5, 6 and 7, it will be noted that a 90 ledger bar 44 has spaced upstanding guide posts 45 on which reciprocates a cutter bar 46. Adjustably secured to this cutter bar by a bolt 47, is a cutting blade 48, that cooperates with the ledger bar 44 to sever the 100

strip 23 that passes over the runway 28 between such ledger bar 44 and cutter blade 48, when the blade is in its elevated position. This elevation is secured by coiled springs 49 mounted on the posts 45 beneath the head 46. As shown in Figure 5, the free end of the arm 43 has a roller 50 that operates on the upper end of the head 46. With this arrangement, it will be evident that as the cam 33 is rotated, its high part, shown in Figure 5, upon each complete revolution, will cause a depression of the bell crank 41—42, 43, and thus depress the cutter, severing a section from the strip 23, as shown in Figure 5, this section constituting a tab.

The movement of the cam 33 is, however, controlled, and the following mechanism is employed for that purpose. The hub 32 of the cam is provided with a wheel 51, which as shown in Figure 10, is provided with five peripherally projected teeth 52, though the number may be altered, as desired. Co-operating with these teeth is a detent escapement, which consists of an arm 53 pivoted on the frame as shown at 54, and having a detent terminal tooth 55 adapted to drop behind the successive teeth 52, and when in this position, it obviously holds the wheel 30 and the cam against rotation with the shaft 30. An over-throw-preventing pawl 56 is mounted on the arm 53, and has a hooked terminal 57 that moves into the path of a tooth when the detent tooth 55 moves out of engagement with a tooth. This, it is thought, will be evident by a comparison of Figures 2 and 10. A spring 58, engaged with the arm 56, serves to urge the tooth 55 into the path of the teeth 52. The pivot 54 for this detent escapement is in the form of a rock shaft, one end of which carries the said detent escapement; the other end extends through one of the side bars 17, and has fixed to its outer end, and as shown in Figures 1 and 10, a crank arm 59. This crank arm has a bearing projection 60 adapted to be engaged by a cam tooth 61 on a wheel 62 suitably carried by a shaft 63 journaled in the frame.

Also fixed to the shaft 63 is a ratchet wheel 64 that is given a step-by-step movement by means of a pawl 65 operating thereon. This pawl is carried by a swinging arm 66 journaled on the shaft 63, and its rearward movement is determined by a stop screw 67, all as shown in Figure 1. Pivotally connected to the free end of the pawl-carrying arm 66, is a reciprocable actuating arm 68. The free portion 69 of said arm is connected to the pivoted portion by a leaf spring 70, which thus permits said portion 69 to have a yielding lateral movement. The rear side of the portion 69 of the actuating arm is provided with a shoulder 71. The front end of the drive shaft

30 carries a wheel 72, provided with an outstanding pin 73 and the shoulder 71 of the arm 69 is so disposed that while it is normally out of the path of the pin 73, by swinging said arm inwardly, it will be brought into the path of the pin 73 and the arm is thus drawn forwardly. The consequence is that the pawl 65 is moved in a corresponding direction and being engaged with a tooth of the ratchet wheel, will give a partial rotation to the said wheel, and consequently to the wheel 62. The return longitudinal movement of the arm 69 is secured by a coiled spring 74, connected to the rear end of the said arm and the arm 66. The arm 69 is slidably supported on a pin 75 projecting from the frame, and its outward movement is limited by a stop 76 that overhangs it.

Directly beneath the free end of the arm 69 is a carrier roller 77, over which the sheets pass and on which they are supported. Coacting with this carrier roller is a strip or caliper device in the form of a swinging cam 78. This cam is pivoted, as shown at 79, on a swinging arm 80 that is pivoted, as illustrated at 81, to the side frame. The arm has a rearward extension 82 borne against on one side by a spring 83 and engaged on its opposite side by an adjusting screw 84. By adjusting said screw 84, it will be evident that the cam 78 of the strip can be moved away from or toward the roller 77, and thus its position adjusted, according to the thickness of the sheet that passes over the roller. This strip has an upstanding arm 85 carrying an adjustable counter-weight 86, and it also has an upstanding finger 87 that is adapted to ride against a cam track 88 carried by the free end of the arm 69. By referring to Figure 8, it will be noted that this cam track 88 is in the form of a spring secured at its outer end on a block 89 fastened to the outer side of the arm 69, thus providing a space behind the cam track.

The feed rollers 25—26 for the strip in this embodiment, are shown as being rotated from the shaft 63. To this end, as illustrated in Figure 3, the inner end of said shaft 63 has fixed to it a gear wheel 90, while the shaft of the lower feed roll 25 has on its inner end a gear wheel 91. Connecting these two gear wheels is an intermediate idler gear 92 mounted on a spindle 93 that is adjustable in an arcuate slot 94 formed in the side bar frame 17. The mounting 93 thus permits the use of gear wheels 92 of different diameters in order to change the speed of the feed roll 25 and thus vary the amount of strip that is fed from the drum between each severance.

The free end portion of the strip 23 that is passed through the cutting mechanism is, until severed, supported on a track 95, shown in detail in Figures 11 and 12. This

track, as illustrated in Figure 1, extends first and the tab drops at an inclination. The result is that the succeeding sheet will slide over it. Otherwise said succeeding sheet is apt to crumple up the tab and push it along ahead of it. It will thus be evident that when a predetermined number of sheets, as A in Figure 1 have passed the mechanism, a tab B is cut off and dropped upon the last of the lot, whereupon another series of a predetermined number of sheets is deposited, to be indicated by another tab, the number depending on the teeth of the ratchet wheel 64, and the teeth on the detent wheel 51. For example, if the ratchet wheel is provided with fifty teeth and the detent wheel with five teeth, two hundred and fifty sheets will be deposited between each tab.

10. 15. 20. 25. 30. 35. 40. 45. 50. 55. 60. 65. 70. 75. 80. 85. 90. 95. 100. 105. 110. 115. 120. 125. 130.

The operation of the device is as follows: It will be understood that the driving shaft 30 is continuously rotated, and that sheets to be counted and tabbed are carried by any suitable means successively over the roller 77. As the front end of each sheet moves over the roller, its upper surface will engage the trip cam 75, so that said cam will be swung in the direction of the arrow in Figure 1. The consequence is that the upper finger 87 will ride against the cam track 88, and thus swing the arm 69 rearwardly, so that its shoulder 71 is brought into the path of the rotating pin 73. The result is that the arm 69, with its connection 70 and 68, is moved longitudinally, thereby turning the pawl 65 and giving the ratchet wheel 64 an increment of movement. The longitudinal movement of the arm, by the pin 73 carries the cam track 88 beyond the finger 87, and if the arm does not move back quickly enough it can swing outwardly so that when it returns the upper end of the finger 87 is behind the cam track and can thus advance to its initial position for another movement by a succeeding sheet. It will thus be evident that the wheel 62 is given a step-by-step rotation, and on each complete rotation, its tooth 61 will operate against the tooth 60 of the detent escapement. When the escapement is thus moved to the position shown in Figure 10, the friction clutch 33-39 between the drive shaft 30 and the cam wheel 51 will permit an increment of movement of said wheel. Upon a complete movement of the wheel 51, the cam 33, as illustrated in Figure 5, will be moved to a position to depress the cutter. During these various preliminary movements prior to the operation of the cutter, the gears 90, 91 and 92 have also been operating to feed the strip through the cutter and out on to the supporting plate 95, this strip being creased by the tongue and groove of the two rollers 25 and 26, and having its free end supported at an upward inclination on said plate 95. When severance takes place, the severed section becomes a tab, and its rear portion is depressed by the finger 97, so that said end drops downwardly.

It sometimes happens that it is desired to mark a much smaller number or variable numbers of sheets. Under such circumstances, the modified embodiment illustrated in Figures 13, 14 and 15 may be employed. In order to avoid needless repetition, all the parts corresponding to those above described have been given the same reference numerals. Instead of a detent operating wheel 62 with a single tooth, an endless sprocket chain 98 may be employed, said sprocket chain passing around a sprocket wheel 62^a used instead of the above mentioned toothed wheel 62. The sprocket chain also passes around an upper idler sprocket wheel 99 adjustably supported on a standard 100 carried by the frame. Suitably mounted on this chain are teeth 61^a, which may be placed as near together or as far apart as desired. In fact but one may be utilized, in which case of course a large number of sheets can be passed before a tab is applied. The operation of this device, it will be evident, is precisely the same as the first mentioned embodiment, for whenever a tooth 61^a engages the tooth 60 of the actuating arm 59, the detent is released and if there is but one tooth on the detent wheel 51, an operation of the cutter is permitted. Under such circumstances, it will be evident that if there is an operation after the passage of a small number of sheets, a sufficient amount of the tab strip may not have been advanced to produce a proper length of tab. Means are therefore provided for feeding a longer strip on each operation of the detent escapement. To this end the lower roller 25 is in the present embodiment mounted on a shaft 101 and loosely journaled on said shaft is a threaded sleeve 102, to which is fixed a gear wheel 103 that is operated through a train of gears 104 from a gear 105 fixed to the drive shaft 30. A spring-pressed friction collar 106 operates against a friction disk 107 that in turn presses against the flange 108 of a hub 109 fixed to the shaft 101, and this hub 109 carries a wheel 110 provided with a stop shoulder 111.

The detent, as shown in Figure 15, has an arm 112 provided with a terminal tooth 113 that lies in the path of the shoulder 111. Consequently while the sleeve with its friction collar 106 is constantly rotating, the shaft 101 is stationary. Whenever the detent is operated, however, the tooth 113 is withdrawn from behind the shoulder 111 and the shaft is rotated through the friction clutch, thus running off sufficient of the strip to produce a tab that will be cut off on the succeeding operation.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim, is:—

1. In apparatus of the character set forth, the combination with a number determining member, of a rotatable driving member, a constantly operated actuating device for the number determining member having a clutch connection with the driving member, a member for normally holding the actuating device against movement by the driving member through said clutch, and means controlled by the articles to be counted for periodically operating the member to permit the driving member to operate the actuating device through said clutch and thereby to operate the number determining member.

2. In apparatus of the character set forth, the combination with a number determining member, of a constantly operating rotatable driving member, an actuating device for the number determining member having a friction clutch connection with the driving member, a pawl for normally holding the actuating device against movement by the driving member, and means controlled by the articles to be counted for periodically operating the pawl to permit the driving member to operate the actuating device and thereby to operate the number determining member.

3. In apparatus of the character set forth, the combination with a number determining member, of a constantly rotated drive shaft, a rotatable actuating device for the member mounted on the shaft and having a friction clutch connection therewith, a swinging escapement pawl that engages the device to hold it against rotation by the shaft, and mechanism controlled by the articles to be counted, for periodically swinging the escapement to permit the shaft to operate the actuating device.

4. In apparatus of the character set forth, the combination with a number determining member, of a drive shaft, a rotatable actu-

ating cam for the member mounted on the shaft and having a friction clutch connection therewith, a lever operated by the cam and operating the number-determining member, said actuating cam having a plurality of teeth, a swinging escapement member having a holding pawl and an overthrow preventing pawl that alternately engage the teeth, and mechanism controlled by the articles to be counted for swinging the escapement member and permitting the cam to be intermittently moved by the shaft.

5. In apparatus of the character set forth, the combination with an article operated trip and means for moving articles successively past the same, of a number determining member, actuating mechanism for the number determining member, a controller for the actuating mechanism of the number determining member, and means for operating the controller, said operating means comprising an actuating member and an actuated member relatively movable into and out of engagement, and means operated by the trip for relatively moving said members.

6. In apparatus of the character set forth, the combination with an article operated trip and means for moving articles successively past the same, of a number determining member, actuating mechanism for the number determining member, a controller for the actuating mechanism of the number determining member, and means for operating the controller, said operating means comprising a rotary actuating member, an actuated member movable into and out of the path of a portion of said rotary member, and a device operated by the trip for moving the actuated device into said path.

7. In apparatus of the character set forth, the combination with an article operated trip and means for moving articles successively past the same, of a number determining member, actuating mechanism for the number determining member, a controller for the actuating mechanism of the number determining member, and means for operating the controller, said operating means comprising a rotary actuating member, a yielding actuated member normally out of the path of the actuating member but movable into said path, and a device operated by the trip for moving the actuated device into said path and then allowing it to again move out of said path.

8. In apparatus of the character set forth, the combination with a sheet carrier and a swinging trip that is engaged and swung by the sheets on said carrier, a number determining member, and mechanism for effecting its actuation including a rotatable actuating member having a tooth, an actuated member that is movable into the path of the tooth to be moved thereby and having a cam, and a finger carried by the trip and operating on

the cam when the trip is swung to move the actuated member into the path of the tooth.

9. In apparatus of the character set forth, the combination with a sheet carrier and a swinging trip that is engaged and swung by the sheets on said carrier, a number determining member and mechanism for effecting its actuation including a rotatable actuating member having a tooth, a longitudinally reciprocatory actuated member having a lateral movement into the path of the tooth, and means operated by the trip for laterally moving the actuated member.

10. In apparatus of the character set forth, the combination with a sheet carrier and a swinging trip that is engaged and swung by the sheets on said carrier, a number determining member and mechanism for effecting its actuation, including a rotatable actuating member having a tooth, a longitudinally reciprocatory actuated member having a lateral movement into the path of the tooth, one end of said actuated member adjacent the actuating member having a cam, and a finger carried by the trip and operating against the cam to laterally move the actuated member.

11. In apparatus of the character set forth, the combination with a number determining member, of an actuating device therefor, a movable controlling member for the actuating device, a device for periodically moving the controlling member, and means controlled by the articles to be counted for giving a step by step movement to the controlling member moving device, said moving device having a predetermined number of step-by-step movements between its operations of the controlling member.

12. In apparatus of the character set forth, the combination with a number determining member, of an actuating device therefor, a movable controlling member for the actuating device, a cam for periodically moving the controlling member, and means controlled by the articles to be counted for giving a step-by-step movement to the cam.

13. In apparatus of the character set forth, the combination with a number determining member, of an actuating device therefor, a movable controlling member for the actuating device, a cam for periodically moving the controlling member, a ratchet wheel for moving the cam step-by-step, a pawl for operating the ratchet wheel, a rotary actuating device, a pawl moving member having a portion movable into and out of the path of the actuating device, and a trip operated by the articles to be counted and having means for moving the pawl moving member into the path of the actuating device.

14. In apparatus of the character set forth, the combination with a number determining member, of an actuating device therefor, a movable controlling member for

the actuating device, a cam for periodically moving the controlling member, a ratchet wheel for moving the cam step-by-step, a pawl for operating the ratchet wheel, a rotary actuating device, a longitudinally movable arm connected to the pawl for moving it, said arm being laterally movable into and out of the path of the actuating device, and a trip operated by the articles to be counted and having a finger for moving the arm laterally into said path.

15. In apparatus of the character set forth, the combination with a number determining member, of a bell crank having one arm operating on the number determining member, a cam for operating on the other arm, a shaft on which the cam is loosely mounted, a friction clutch between the shaft and cam, a toothed wheel fixed to the cam, an escapement member cooperating with the toothed wheel for permitting its and the cam's periodic movement, a cam element for periodically operating the escapement member, a ratchet wheel for effecting the movement of the cam element, a pawl operating on the ratchet wheel, a toothed wheel fixed to said shaft, an arm connected to the pawl and movable into and out of the path of the tooth of the wheel, a sheet carrier, a trip moved by the sheets on the carrier, and a finger moved by the trip and operating the arm to move it into the path of the tooth.

16. In apparatus of the character set forth, the combination with sheet carrying means, of a cutter, means for advancing a strip through the cutter and above the path of the sheets, means for actuating the cutter, mechanism including a device engaged and actuated by the successive sheets, for operating the cutter to sever a section of the strip when a predetermined number have passed, and means for depositing the severed section at a downward inclination so that a succeeding sheet will be caused to slide over such section.

17. In apparatus of the character set forth, the combination with sheet carrying means, of a cutter, means for advancing a strip through the cutter and above the path of the sheets, a support for the free end of the advanced strip, and mechanism, including a device engaged and actuated by the successive sheets, for operating the cutter to sever the section of the strip advanced therethrough, said support permitting the severed end to drop first.

18. In apparatus of the character set forth, the combination with sheet carrying means, of a strip carrying drum, a strip cutter, coacting feed rollers for advancing the strip from the drum past the cutter, a drive shaft, a cutter actuating cam having a friction clutch connection with the drive shaft, a detent for holding the cam against movement by the shaft, a cam element for mov-

ing the detent, a ratchet wheel connected to the cam element, a pawl operating on the ratchet wheel, a toothed wheel carried by the drive shaft, an arm connected to the pawl and having a portion movable into and out of the path of the tooth, a trip engaged and operated by the successive sheets and having means for engaging the arm to move it into the path of the tooth, means for moving the feed rollers to advance the strip while the cutter is inactive, and means for causing the section of the strip severed by the cutter to drop upon the last of a predetermined number of sheets that have actuated the trip.

19. In apparatus of the character described, the combination with article carrying means, of a driving member, a number-determining device, means driven by the driving member for operating the number-determining device, a controller for holding said means inactive, an actuating device for moving the controller to a position to permit the driving member to operate the number-determining member, an element for intermittently moving the actuating device, and means actuated by the article carried by said carrying means for intermittently connecting the element to the driving member.

20. In apparatus of the character described, the combination with a main rotatable driver, of a movable number-determining member, means for causing the main driver to operate the number-determining member, mechanism for normally preventing the main driver from actuating the number-determining member, an article conveyor, means actuated by articles on the conveyor for causing the main driver to operate the mechanism and permit said main driver to actuate the number-determining member after a predetermined number of articles have been conveyed by the conveyor.

21. In apparatus of the character described, the combination with a number-determining member, of a main driver, an article conveyor, and mechanism for effecting the operation of the number-determining member, including an actuating member that detachably engages the main driver, and a device in the path of the articles on the conveyor and operated thereby to move the actuating member into position to be moved by the main driver.

22. In apparatus of the character described, the combination with a number-determining member, of a rotatable main driver having a crank element, an article conveyor, and mechanism for effecting the operation of the number-determining member including an actuating member having a back and forth movement, said actuating member being movable into and out of the path of the crank element to be moved there-

by, and a device actuated by the articles on the conveyor for moving the actuating member into the path of the crank element.

23. In apparatus of the character described, the combination with a strip cutter, of means for feeding a strip past the same, a conveyor for articles, a device successively operated and having its operation controlled by the articles carried by the conveyor, a second device capable of successive operations and having its operation controlled by a predetermined number of operations of the first device, and actuating means for the cutter that is operable to move the cutter after a predetermined number of operations of the second device.

24. In apparatus of the character described, the combination with a strip cutter, of means for feeding a strip past the same, a conveyor for articles, a main driver, a device adapted to be successively operated, means actuated by the articles on the conveyor and successively connected to the main driver for moving said device, a second device operable by the main driver, means actuated by the first device upon a predetermined number of movements thereof to permit the actuation of the second device by the main driver, and means driven by the main driver and operating the cutter on a predetermined number of movements of the second device.

In testimony whereof, I affix my signature.

ALBERT BROADMEYER.
